(57) **CLAIM**

The ornamental design for an adjustable ladder stabilization device, as shown and described.

DESCRIPTION

FIG. 1 is a front perspective view showing my new design; FIG. 2 is a front elevational view thereof; FIG. 3 is a rear elevational view thereof; FIG. 4 is a right-side elevational view thereof; FIG. 5 is a left-side elevational view thereof; FIG. 6 is a top plan view thereof; FIG. 7 is a bottom plan view thereof; FIG. 8 is an angled elevational view showing the top and front sides thereof; FIG. 9 is an angled elevational view showing the top and rear sides thereof; and, FIG. 10 is a rear perspective view thereof. The broken lines illustrate mechanical fasteners of the adjustable ladder stabilization device that form no part of the claimed design.

1 Claim, 10 Drawing Sheets
